Application March 6, 1953, Serial No. 340,684

8 Claims. (Cl. 70—451)

The present invention provides an easily-installed support for a conventional latch mechanism mounted in a hollow structure. The almost exclusive use of wood in the past as the material of which doors were manufactured is partially giving way to the use of fabricated sheet metal structures, and also to the use of hollow extruded sections. With the wood door, the mounting of the latch mechanism involves no problem of providing support, since the bore in which the mechanism is inserted provides a substantially continuous cylindrical surface which can be as snug a fit as appears to be desirable. When this portion of the door is a hollow structure of sheet metal on the order of a sixteenth of an inch in thickness, an entirely different situation is present. Under these circumstances, the walls of the hollow door structure are capable of providing support to the latch mechanism only at the edge of the door where the mechanism intersects the wall. Under most circumstances, the diameter or thickness of the latch mechanism will be less than the space between the opposite walls, and the inner extremity of the latch mechanism will therefore be left unsupported against movement in the direction perpendicular to the plane of the door. Even if the walls have a spacing closely approximating the thickness of the latch mechanism, there still will be no support against angular movement in the plane of the door with the mechanism tending to pivot about the point where it emerges from the edge of the hollow structure. The installation of extra equipment during the manufacture of the door to stabilize the inner end of the latch mechanism is a rather cumbersome and expensive operation in view of the necessity of cutting out enough of the wall structure to permit the necessary equipment to be installed. Extra fastenings and other similar items most certainly will adversely affect the cost of the entire installation.

The present invention provides a support for the inner end of the latch mechanism without the necessity of tearing apart the door structure in this area. Installation of the supporting member is made at the aperture provided for the insertion of the transverse bar operating the roll-back mechanism. A somewhat larger aperture than would be necessary merely for the passage of the bar is used in order to accommodate the present invention, but the size of this aperture is such that it can easily be covered by the molded area of the knob or by a suitable escutcheon, if desired.

The supporting member is preferably formed of spring steel or some similar material which will permit a considerable yielding action. In the "free" condition, the member is arcuate in form, and has a chordal length somewhat in excess of the diameter of the hole in the wall of the structure through which it is to be inserted. Insertion through the hole therefore requires a considerable amount of deflection; and on arrival at its fully installed position, suitable abutments are provided on the member permitting it to snap into a position from which it cannot be withdrawn except by again deflecting it. The supporting member contains an aperture adapted to re-

2

ceive the inner end of the latch mechanism, and the insertion of the latch mechanism through this aperture would tend to limit or remove a considerable amount of the natural resilience of the piece so as to establish a locking action preventing inadvertent removal of the supporting member from its installed position. The overall effect of the supporting member is simply to transfer the forces applied to the housing of the latch mechanism over to the walls of the hollow structure. This transfer of forces is accomplished while maintaining the axis of the latch mechanism in its proper relationship with the door structure. Several modifications of the present invention are discussed herein.

The several features of the present invention will be discussed in detail through an analysis of the particular embodiments illustrated in the accompanying drawings. In the drawings,

Figure 1 shows a perspective view of a latch mechanism installed in a hollow door structure, with the inner end supported by a clip constructed according to the present invention. A portion of the door structure is broken away for clarity.

Figure 2 is a view of the supporting clip shown installed in Figure 1.

Figure 3 is a section taken on the plane 3—3 of Figure 2.

Figure 4 is a view showing the supporting clip in the position in which it is inserted.

Figure 5 shows a modified form of the present invention provided with a locating tab for orienting the supporting clip with respect to the axis of the latch mechanism.

Figure 6 is a further modification of the present invention, also provided with orienting means.

Figure 7 is a sectional view showing the installation of a modified form of the present invention requiring an aperture in only one wall of the hollow structure.

Figure 8 shows a further modification of the present invention.

Referring to Figure 1, a latch mechanism designated generally at 10 is shown mounted in the hollow siderail 11 of a door. This member is shown formed as an extruded section (usually of aluminum) having the opposite walls 12 and 13 between which the latch mechanism 10 is positioned. An angular portion formed by the back wall 14 and the extension 15 accommodates glass, screen, or any other convenient panel material. The front wall 16 of the rail 11 is conventionally bored with an aperture of sufficient size to receive the latch mechanism 10, and the mechanism may be retained in position with respect to preventing outward movement by the provision of a flange 17 on the housing of the latch mechanism 10 which cooperates with the opposite keyways 18 and 19 in the rail 11. The provision of opposite flats (one of these indicated at 20) permits the insertion of the flange into the keyways 18 and 19 when the latch mechanism is turned about its axis approximately ninety degrees from the position shown in Figure 1. The dimension across the flats must of course be less than the distance between the ridges 21 and 22. The insertion of the latch mechanism at a position ninety degrees removed from that shown in Figure 1 is made prior to the insertion of the transverse bar 23, which is installed after the latch mechanism has been positioned as shown.

The installation of the latch mechanism 10 in this fashion will result in establishing a firm support for the outer end adjacent the bolt 24. The inner end 25, however, will be left suspended unless further structure is utilized. To provide support in this area, a clip 26 is positioned as shown in Figure 1. The installation of the clip 26 is made through the opening 27 machined in the wall 12 of the rail 11. An opening substantially coaxial

with the opening 27 is necessary to accommodate the cross bar 23, so the forming of the opening 27 is not in any sense an additional operation to that which would be required without the present invention. Preferably, an opening 28 similar to 27 is provided in the opposite wall 13, and the clip 26 constructed to cooperate with both of these openings.

The construction of the clip 26 is most clearly indicated in Figures 2 and 3. In the form shown in the drawings, this clip is essentially an arcuate panel formed of a resilient material (preferably spring steel) and having a central hole 29 to accommodate the latch mechanism 10. A portion of the arcuate panel section extends between the opposite walls 12 and 13, and abutment means as indicated at 30 and 31 are formed by the flanges 32. The chordal distance or length 33 (refer to Figure 3) across the outer extremities of the flanges 32 is greater than the diameter of the aperture 27. Insertion of the clip 26 in the aperture 27 is therefore accomplished as shown in Figure 4 through an application of forces in the direction of the arrows tending to deflect the clip a sufficient amount to permit the passage through the aperture. Such deflection results in decrease of the chordal length 33. On release of the forces, the clip springs outwardly so that the flanges 32 are retained between the walls 12 and 13. If desired, tabs as indicated at 34 and 35 may be used to supplement the abutments 30 and 31 so that the clip 26 will be positioned between the walls 12 and 13 at several points.

The installation of the clip 26 is made prior to the insertion of the latch mechanism 10. After the clip 26 has been positioned and the latch mechanism inserted in the assembled relationship shown in Figure 1, the presence of the latch mechanism 10 in the opening 29 of the clip 26 serves to considerably limit the deflection of the clip 26 and to thereby lock it against accidental displacement which might disengage the abutments 30 and 31. The clip 26 is preferably provided with the tabs 36 and 37 formed of material adjacent the opening 29, the distance between the free ends of these tabs being less than the thickness of the latch mechanism at this point. The insertion of the latch mechanism therefore causes the tabs 36 and 37 to resiliently bear on the housing, and to give solid support regardless of the accumulation of manufacturing tolerances. A further function of the tabs 36 and 37 is to permit only a one-way relative movement between the clip 26 and the latch mechanism 10. Due to the fact that the tabs 36 and 37 engage the housing of the latch mechanism 10 at an angle, movement of the housing in an outward direction would tend to cause the tabs 36 and 37 to bite more firmly into the housing and establish a jamming action. If means are utilized to securely locate the supporting clip 26 within the aperture 27 against movement parallel to the axis of the latch mechanism, it is possible to utilize the tabs 36 and 37 to perform the entire function of locating the latch mechanism within the door rather than rely upon the engagement of the flange 17 with the keyways 18 and 19. Under these circumstances, the flange 17 may be reduced in diameter to where it is free to pass between the flanges 21 and 22, the flange 17 then being utilized merely to limit the degree of movement of the mechanism within the door during installation.

In Figure 5, a modification of the present invention is shown which is provided with means for properly orienting the clip about the axis of the aperture in which it is installed. The transverse aperture 39 formed in the wall 40 of the door is similar to the aperture 27 shown in Figure 1. Prior to the drilling of the opening 39, however, a smaller hole 41 is drilled, with its center approximately intersecting the position of the periphery of the hole 39. After the hole 41 is drilled, the machining of the hole 39 will intersect the hole 41 to form an arcuate recess which can be used to orient the clip so that the

aperture 29 is properly disposed to receive the latch mechanism 10.

The use of opposite apertures 42 and 43, as shown in Figure 6, which are formed in a similar fashion to the aperture 41 of Figure 5, may be used to orient the clip 44 and also serve the purpose of positively positioning the clip against movement parallel to the axis of the latch mechanism. The tabs 45, 46, and 47 are positioned to project into the aperture 48, and the remainder of the panel portion of the clip 44 is of such a dimension as to be positioned between the inner and outer walls of the supporting structure.

Figure 7 indicates a modified form of the present invention illustrating use in situations in which an aperture is feasible in only one side of the door. The clip 49 is positioned between the walls 50 and 51, with a projection portion 52 extending into the aperture 53. The end 54 of the clip and also the shoulders 55 at the ends of the flanges 56 form opposite abutments transferring forces to the walls 50 and 51 applied at the aperture 57 by a latch mechanism.

A supporting clip may also be formed as indicated in Figure 8 in such a fashion as to substantially exceed one hundred eighty degrees of curvature. Under these circumstances, however, cut-away portions as indicated at 58 and 59 must be installed to permit the insertion of the latch mechanism through the supporting aperture 60. With the clip 61 formed in a substantial portion of a complete cylinder at points where it engages the walls of the door structure, the clip will present a considerable stability against displacement parallel to the axis of the latch mechanism.

The particular embodiments of the present invention which have been illustrated and discussed herein are for illustrative purposes only, and are not to be considered as a limitation upon the scope of the appended claims. In these claims, it is our intention to claim the entire invention disclosed herein, except as we are limited by the prior art.

We claim:

1. A supporting clip for a member mounted in a hollow structure having opposite holes in the walls thereof, said clip comprising: an arcuate panel portion having axial flanges forming axially spaced abutment portions at the ends of said flanges, said clip being formed of resilient material and having an unrestrained form such that the chordal distance between the outer extremities of said flanges exceeds the diameter of said holes, the axial distance between the ends of said flanges being less than the inside distance between the opposite walls of said hollow structure at said holes; projections extending axially beyond the ends of said flanges for disposition within said holes in bearing engagement with said walls at a plurality of substantially spaced points around each of said holes, said clip having a chordal length between the said projections at one end of said clip which is less than the chordal distance between the outer extremities of said flanges; and means defining an aperture associated with said panel and adapted to receive said member with said projections engaging said holes, said clip having at least one tab adjacent said aperture and disposed to resiliently engage said member on an angle.

2. A supporting clip for a member mounted in a hollow structure having opposite holes in the walls thereof, said clip comprising: an arcuate panel portion having axially spaced abutment portions and formed of resilient material, and having an unrestrained form such that the chordal distance between the outer extremities of said abutment portions exceeds the diameter of said holes, the axial distance between said abutment portions being less than the inside distance between the opposite walls of said hollow structure at said holes; projections extending axially beyond the ends of said abutment portions for dis-

tion within said holes in bearing engagement with said walls at a plurality of substantially spaced points around each of said holes, said clip having a chordal length between the said projections at one end of said clip which is less than the chordal distance between the said outer extremities of said abutment portions; and means defining an aperture associated with said panel and adapted to receive said member with said projections engaging said holes, said clip having opposite chordal tabs adjacent said aperture and disposed to resiliently engage said member on an angle.

3. A supporting clip for a member mounted in a hollow structure having opposite holes in the walls thereof, said clip comprising: an arcuate panel portion having axially spaced abutment portions and formed of resilient material, and having an unrestrained form such that the chordal distance between the outer extremities of said abutment portions exceeds the diameter of said holes, the axial distance between said abutment portions being less than the inside distance between the opposite walls of said hollow structure at said holes; projections extending axially beyond said abutment portions for disposition within said holes in bearing engagement with said walls at a plurality of substantially spaced points around each of said holes, said clip having a chordal length between the said projections at one end of said clip which is less than the chordal distance between the said outer extremities of said abutment portions; and means defining an aperture associated with said panel and adapted to receive said member with said projections engaging said holes, said clip having at least one tab adjacent said aperture and disposed to resiliently engage said member on an angle.

4. A supporting clip for a member mounted in a hollow structure having opposite holes in the walls thereof, said clip comprising: an arcuate panel portion having axially spaced abutment portions and formed of resilient material, and having an unrestrained form such that the chordal distance between the outer extremities of said abutment portions exceeds the diameter of said holes, the axial distance between said abutment portions being less than the inside distance between the opposite walls of said hollow structure at said holes; projections extending axially beyond the said abutment portions a distance less than the thickness of the adjacent wall of said hollow structure for disposition within said holes in bearing engagement with said walls at a plurality of substantially spaced points around each of said holes, said clip having a chordal length between the said projections at one end of said clip which is less than the chordal distance between the said outer extremities of said abutment portions; and means defining an aperture associated with said panel and adapted to receive said member with said projections engaging said holes.

5. A supporting clip for a member mounted in a hollow structure having opposite holes in the walls thereof, said clip comprising: an arcuate panel portion having axially spaced abutment portions and formed of resilient material, and having an unrestrained form such that the chordal distance between the outer extremities of said abutment portions exceeds the diameter of said holes, the axial distance between said abutment portions being less than the inside distance between the opposite walls of said hollow structure at said holes; projections extending axially beyond the said abutment portions for disposition within said holes in bearing engagement with said walls at a plurality of substantially spaced points around each of said holes, said clip having a chordal length between the said projections at one end of said clip which is less than the chordal distance between the said outer extremities of said abutment portions; and means defining an aperture associated with said panel and adapted to receive said member with said projections engaging said holes.

6. A supporting clip for a member mounted in a hollow structure having a hole in at least one wall thereof, said clip comprising: an arcuate panel portion having axially spaced abutment portions and formed of resilient material, and having an unrestrained form such that the chordal distance between the outer extremities of said abutment portions exceeds the diameter of said hole, the axial distance between said abutment portions being less than the inside distance between the opposite walls of said hollow structure at said hole; a projection extending axially beyond one of the said abutment portions for disposition within said hole in bearing engagement with said wall at a plurality of substantially spaced points around said hole, said clip having a chordal length across the said projection which is less than the chordal distance between the said outer extremities of said abutment portion; and means defining an aperture associated with said panel and adapted to receive said member with said projection engaging said hole, said clip having at least one chordal tab adjacent said aperture and disposed to resiliently engage said member on an angle.

7. A supporting clip for a member mounted in a hollow structure having a hole in at least one wall thereof, said clip comprising: an arcuate panel portion having axially spaced abutment portions and formed of resilient material, and having an unrestrained form such that the chordal distance between the outer extremities of said abutment portions exceeds the diameter of said hole, the axial distance between said abutment portions being less than the inside distance between the opposite walls of said hollow structure at said hole; a projection extending axially beyond one of the said abutment portions a distance less than the thickness of the adjacent wall of said hollow structure for disposition within said hole in bearing engagement with said wall at a plurality of substantially spaced points around said hole, said clip having a chordal length across the said projection which is less than the chordal distance between the said outer extremities of said abutment portion; and means defining an aperture associated with said panel and adapted to receive said member with said projection engaging said hole.

8. A supporting clip for a member mounted in a hollow structure having a hole in at least one wall thereof, said clip comprising: an arcuate panel portion having axially spaced abutment portions and formed of resilient material, and having an unrestrained form such that the chordal distance between the outer extremities of said abutment portions exceeds the diameter of said hole, the axial distance between said abutment portions being less than the inside distance between the opposite walls of said hollow structure at said hole; a projection extending axially beyond one of the said abutment portions for disposition within said hole in bearing engagement with said wall at a plurality of substantially spaced points around said hole, said clip having a chordal length across the said projection which is less than the chordal distance between the said outer extremities of said abutment portion; and means defining an aperture associated with said panel and adapted to receive said member with said projection engaging said hole.
